METHOD FOR CONTROLLING THE FLOW
OF GASES

Julius M. Naiman, Detroit, Mich.

Application April 2, 1940, Serial No. 327,472

1 Claim. (Cl. 137—78)

This invention relates to a method of distributing gases or vapors to a plurality of parallel zones and more particularly to a method of distributing gases from an inlet header to a bank of tubes.

An object of the invention is to maintain a predetermined gas distribution to a set of tubes regardless of variations in the pressure drops or in the operating conditions within the individual tubes.

Another object is to provide a system of the above type in which changes in operating conditions in one tube of a bank are prevented from affecting the rate of gas flow to the other tubes of the bank.

Another object is to provide a means for effecting the above control which is automatic in operation and which does not require careful adjustment.

Another object is to provide a system for effecting a desired distribution of gases to a plurality of banks of tubes in a converter furnace.

Another object is to provide an efficient, dependable and commercially practical system of the type above indicated.

Various other objects and advantages will be apparent as the nature of the invention is more fully disclosed.

In accordance with the present invention, the above objects are attained by utilizing the critical velocity of a gas through a passage such as an orifice, nozzle, Venturi tube or the like. It has been found, for example, that when the absolute pressure on the high pressure side of such a passage bears a definite relationship to the absolute pressure on the low pressure side thereof, there exists a condition of maximum velocity and maximum gas flow through the passage for that particular high pressure. This maximum velocity is referred to herein as the critical velocity of the passage. When a passage of the above type is operated under critical pressure conditions, changes in pressure on the low pressure side do not affect the rate of gas flow therethrough, provided the pressure at no time exceeds that required for the critical velocity relationship. Consequently, by incorporating such passages in the individual tubes of a bank and operating the bank of tubes so that the condition of critical velocity exists, variations in pressure within the tubes themselves produced, for example, by changes in pressure drop within the tubes, do not change the rate of gas flow either in the individual tubes or in the bank of tubes.

This invention is particularly useful for dis-

tributing gases to a catalytic converter in which the pressure drop within the individual catalyst tubes may vary due to carbon deposition or other change in the condition of the catalyst, and permits the gas distribution to and through the tubes to be maintained in a predetermined relationship, which is unaffected by conditions within the converter itself, at least until the pressure drop within an individual tube has increased to a point such that the critical velocity relationship no longer exists.

The critical velocity condition of an orifice nozzle, Venturi tube or other passage depends upon the shape of the particular passage. Critical velocity conditions exist through a sharp edge orifice, for example, when the absolute pressure on the high pressure side is at least double the absolute pressure on the low pressure side. The conditions for other passages may be readily computed or determined.

Although the novel features which are believed to be characteristic of this invention are pointed out more particularly in the claim appended hereto, the invention itself may be better understood by referring to the following description, taken in connection with the accompanying drawing, in which a specific embodiment thereof has been set forth for purposes of illustration.

30 In the drawing,

Fig. 1 is a sectional view through a portion of a converter embodying the present invention;

Fig. 2 is an enlarged detail view showing the arrangement of the orifice plates; and

35 Fig. 3 is a section taken on the line 3—3 of Fig. 2.

Referring to the drawing more in detail, the invention is shown as applied to a converter 10 which is intended to represent diagrammatically a tube still, a catalytic converter or other device employing a plurality of banks of tubes 11 to which gases are to be distributed.

The tubes 11 are shown as arranged in four banks. The tubes of each bank communicate 45 with a separate header 14. Gases are supplied to the headers 14 from an inlet pipe 15 through branches 16 and valves 17, by means of which the pressure of the gases in the different headers 14 may be controlled.

50 Each of the tubes 11 is shown in Figs. 2 and 3 as provided with a coupling flange 20 which is adapted to be clamped by bolts 21 against a coupling flange 22 on a nipple 24 communicating with the header 14. In the embodiment shown an orifice plate 25 is clamped between the

flanges 20 and 22. This orifice plate is shown as provided with a gas passage or orifice 26 of the sharp edge type. It is to be understood, however, that the gas passage may be of other types, such as a flared orifice, a nozzle or a Venturi tube which, with suitable changes in the operating conditions, may be made to function in the manner herein described.

The system above described is operated so that critical velocity conditions are maintained through the gas passage. With a sharp edge orifice, as shown, the absolute pressure in the headers 14 is maintained at least double the absolute pressure on the low pressure side of the plates 26. For example, if the gases are supplied through the pipe 15 to the headers 14 under a pressure of, say, 60 lbs. absolute, the pressure within the tubes 11 should not exceed 30 lbs. absolute.

This latter pressure is governed by the back pressure on the system which may be maintained by suitable valves, not shown. The pressure on the low pressure side of the orifice plates will amount to the sum of the pressure maintained at some further point in the system and the pressure drop between that point and the orifice plate. This pressure drop is dependent, among other things, upon the condition of the material within the tubes, in the case of a catalytic converter, for example, being dependent upon condition of the catalyst as to porosity, free space, etc.

With the system operating as above set forth and assuming an absolute pressure of 60 lbs. in the headers 14, the pressure in the tubes 11 may vary, for example, from 10 lbs. to 28 lbs. without changing the flow through the orifices or the relative distribution of gases to the various tubes. The gas flow is accordingly made independent of the condition of the catalyst and the gas distribution is maintained constant without the necessity for accurate or careful adjustments. Even the complete shut down of one or more tubes will not alter the gas flow through the

remaining tubes provided the critical velocity conditions are still maintained. The invention is accordingly suited for the control of gas flow to a set of catalyst tubes or banks of tubes, some of which are to be periodically removed from stream for reactivation. It is also useful to maintain constant operating conditions in the various tubes of a bank regardless of changes in flow through certain tubes due to carbon deposition or the like.

It is to be understood that the above embodiment of the invention has been given as an illustration only and that the invention may be applied with suitable changes in the pressure relationship to passages of various shapes.

While the invention is particularly applicable to the catalytic treatment of hydrocarbon oils wherein the control of the rate of gas flow is important, it is to be understood that the invention may be put to other uses and that various changes and modifications may be made therein as will be readily apparent to a person skilled in the art. The invention is only to be limited in accordance with the scope of the following claim.

What is claimed is:

The method of controlling the flow of gases through a bank of tubes having flow restricting inlet orifices and connected in parallel between an inlet and an outlet header and in which each of such tubes is subject to varying flow resistances during operation and in a manner such that the flow through each individual tube will be constant regardless of such variations in flow resistance, which method comprises maintaining a constant high pressure in the inlet header and a sufficiently low pressure in the outlet header that the pressure differential across each of said orifices is always sufficient to maintain the differential required for critical flow velocity conditions through each of said orifices notwithstanding variations in flow resistance in any or all of said tubes.
